UNITED STATES PATENT OFFICE

111,512

DESIGN FOR A COVER FOR A VACUUM CLEANER OR SIMILAR ARTICLE

Lurelle Guild, Darien, Conn., assignor, by mesne assignments, to Electrolux Corporation, Dover,
Del., a corporation of Delaware

Application February 26, 1938, Serial No. 75,439

Term of patent 14 years

To all whom it may concern:

Be it known that I, Lurelle Guild, a citizen of the United States of America, residing in Darien, Connecticut, have invented a new, original, and ornamental Design for a Cover for a Vacuum Cleaner or Similar Article, of which the following is a specification, reference being had to the accompanying drawing, forming part thereof.

Fig. 1 is a top view of the cover, showing my new design;

Fig. 2 is a front view of the cover; and

Fig. 3 is a perspective view of the cover.

I claim:

The ornamental design for a cover for a vacuum cleaner or similar article, as shown.

LURELLE GUILD.
